US00D766208S

(12) **United States Design Patent** (10) **Patent No.:** **US D766,208 S**
Paterson et al. (45) **Date of Patent:** **** Sep. 13, 2016**

- (54) **COMMUNICATIONS HEADSET OR HEADPHONE**
- (71) Applicant: **Plantronics, Inc.**, Santa Cruz, CA (US)
- (72) Inventors: **Nicholas W Paterson**, Santa Cruz, CA (US); **Barry C Ferris**, Santa Cruz, CA (US)
- (73) Assignee: **Plantronics, Inc.**, Santa Cruz, CA (US)
- (**) Term: **15 Years**
- (21) Appl. No.: **29/528,461**
- (22) Filed: **May 28, 2015**
- (51) **LOC (10) Cl.** **14-01**
- (52) **U.S. Cl.** **USPC** **D14/205**
- (58) **Field of Classification Search**

Primary Examiner — Paula Greene

(57) **CLAIM**

The ornamental design for a communications headset or headphone, as shown and described.

DESCRIPTION

FIG. 1 is a front-left perspective view of a communications headset or headphone showing my new design;

FIG. 2 is a back-right perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines showing the unclaimed features form no part of the claimed design.

1 Claim, 8 Drawing Sheets
